(57) **CLAIM**

The ornamental design for a display screen with animated graphical user interface, as shown and described.

DESCRIPTION

FIG. 1 is a front view of a first embodiment of a first image of a display screen with animated graphical user interface showing the new design;

FIG. 2 is a front view of a second image of the first embodiment of FIG. 1;

FIG. 3 is a front view of a third image of the first embodiment of FIG. 1;

FIG. 4 is a front view of a fourth image of the first embodiment of FIG. 1;

FIG. 5 is a front view of a fifth image of the first embodiment of FIG. 1;

FIG. 6 is a front view of a sixth image of the first embodiment of FIG. 1;

FIG. 7 is a front view of a seventh image of the first embodiment of FIG. 1;

FIG. 8 is a front view of a second embodiment of a first image of a display screen with animated graphical user interface showing the new design;

FIG. 9 is a front view of a second image of the second embodiment of FIG. 8;

FIG. 10 is a front view of a third image of the second embodiment of FIG. 8;

FIG. 11 is a front view of a fourth image of the second embodiment of FIG. 8;

FIG. 12 is a front view of a fifth image of the second embodiment of FIG. 8;

FIG. 13 is a front view of a sixth image of the second embodiment of FIG. 8; and,

FIG. 14 is a front view of a seventh image of the second embodiment of FIG. 8.

The appearance of the transitional image sequentially transitions between the images shown in FIGS. 1-7 and 8-14. The process or period in which one image transitions to another image forms no part of the claimed design.

(Continued)

The broken lines of uneven length show the display screen and form no part of the claimed design. The broken lines of even length shown in the drawings illustrate portions of the display screen with animated graphical user interface that form no part of the claimed design.
